US0D1107081S

(12) **United States Design Patent** (10) **Patent No.:** **US D1,107,081 S**
(45) **Date of Patent:** **** Dec. 23, 2025**

(54) **CUTTER**

(71) Applicant: **Vermeer Manufacturing Company**,
Pella, IA (US)

(72) Inventor: **Joshua Dean Nossaman**, Pella, IA
(US)

(73) Assignee: **Vermeer Manufacturing Company**,
Pella, IA (US)

(**) Term: **15 Years**

(21) Appl. No.: **29/962,702**

(22) Filed: **Sep. 12, 2024**

(51) LOC (15) Cl. **15-09**

(52) U.S. Cl.

USPC **D15/127**

(58) **Field of Classification Search**

USPC D8/70, 98; D15/17, 28, 127, 133, 138,
D15/139; D18/37.3; D19/69

CPC B26B 19/3853; B26B 19/02; B26B 25/00;
E21B 10/00; B27B 33/142; B26D
2007/2692

See application file for complete search history.

(57) **CLAIM**

The ornamental design for a cutter as shown and described.

DESCRIPTION

FIG. 1 is a front, top, right perspective view of a cutter according to a first embodiment.

FIG. 2 is a front, bottom, left perspective view of the cutter of FIG. 1. FIG. 3 is a left side elevation view of the cutter of FIG. 1.

FIG. 4 is a right side elevation view of the cutter of FIG. 1. FIG. 5 is a front elevation view of the cutter of FIG. 1.

FIG. 6 is a rear elevation view of the cutter of FIG. 1.

FIG. 7 is a top plan view of the cutter of FIG. 1; and, FIG. 8 is a bottom view of the cutter of FIG. 1.

The portions of the cutter shown in broken lines form no part of the claimed design.

1 Claim, 8 Drawing Sheets
